UNITED STATES PATENT OFFICE.

ROBERT J. JOHNSTON, OF KANSAS CITY, MISSOURI, ASSIGNOR OF ONE-HALF TO GEORGE F. ROGGE, OF CORDER, MISSOURI.

APPARATUS FOR MANUFACTURE OF WALL BOARD.

Application filed February 6, 1922. Serial No. 534,454.

To all whom it may concern:

Be it known that I, ROBERT J. JOHNSTON, a citizen of the United States, and resident of Kansas City, county of Jackson, State 5 of Missouri, have invented a certain new and useful Improvement in Apparatus for Manufacture of Wall Board, of which the following is a complete specification.

The present invention relates to apparatus 10 for use in the manufacture of wall boards, such as is used for providing an interior wall facing, and with special reference to that type of wall board which is made up in sections each formed with lips extending 15 longitudinally along its opposite side edges, and continuous with one face of the section, so that these sections are adapted to be arranged in alternately reversed relation with their side lips matched together in 20 lapping relation, for providing a wall board of substantially even and uniform cross section throughout.

Accordingly, I have devised an apparatus which comprises a suitable bed having 25 a supporting surface for the wall board material, together with means for spreading this material into a layer of uniform thickness, and means operating simultaneously to produce continuous lines of depression 30 extending in parallel directions longitudinally of the sheet. In its preferred form, this spreading means comprises a roller traveling longitudinally of the sheet to spread the material, and provided with suitable enlargements which operate in the 35 travel of the roller to produce said lines of depression whereby the wall board is formed with shouldered marginal lips for the purpose described.

With this general object in view, the 40 invention will now be described by reference to the accompanying drawing illustrating one form of construction which I have devised for embodying the proposed improvements, after which the novel features therein will be particularly set forth and claimed.

In the drawing—

Figure 1 is a perspective view showing 45 a portion of a supporting bed with the improved means associated therewith for spreading the wall board material and also producing the marginal shouldered lips, in accordance with the present invention;

Figure 2 is an enlarged transverse sectional view of the same; and 55

Figure 3 is a perspective view illustrating a wall board panel or section of the type adapted to be produced by the operation of the improved apparatus.

Referring now to the drawing in detail, 60 this illustrates an apparatus especially designed for the production of wall board panels or sections 4 in sheet form and having the side margins thereof formed with shouldered lips 5, whereby said panels or 65 sections 4 are adapted to be matched together in alternately reversed relation with the shouldered lips 5 in overlapping relation, all as set forth in detail in my co-pending application, Serial No. 498,743, 70 filed September 6, 1921. These wall board panels or sections 4 are adapted to be produced from such material as straw board, wood pulp, or wood fiber and plaster, while this material is in a plastic condition, the 75 said material being molded or rolled into a substantially uniform thickness, and afterward transferred to an oven for drying.

To provide a practical and quick method and apparatus for producing such wall board panels or sections having the shouldered lips 5, I have devised an apparatus which consists of a bed 6 providing a flat supporting surface, upon which to apply the wall board material in a plastic condition, and 80 roll the same to a uniform layer of the desired thickness. Arranged in parallel relation upon this supporting bed 6 is a pair of frame or form members 7 adapted to be bolted or otherwise fastened by means of 85 bolts or screws 8, to the bed member 6, the required distance apart, according to the desired width of panel or section 4. The bed member 6 is provided with a plurality of series of bolt or screw openings 9 for 90 permitting the said frame or form members 7 to be secured at various distances apart, so that different widths of panels 4 may be 95 produced.

For spreading the material while in its 100 plastic condition into a layer of substantially even thickness, I employ a suitable form of roller 10 of a length substantially equal to the distance between the form of frame members 7, and having the axle 11 105 of the roller provided with suitable guide

projections in the form of guide rollers 12 operating in guide grooves 14 formed in the inner faces of the form members 7, as clearly illustrated in Figures 1 and 2. By means 5 of this guide groove and roller structure, the roller is obliged to travel at a constant distance above the top face of the bed member 6, in order to insure a uniform thickness of panel 4. The opposite ends of the roller, 10 are further provided with suitable enlargements, such as may be formed by a band or collar 15 secured to each end of the roller, so that as the roller is caused to travel in the path provided therefor between the 15 form members 7, the said enlargements represented by said bands or collars 15, will simultaneously depress the material along the side margins adjacent the inner edges of the frames or forms 7, and thus producing 20 the shouldered lips 5 along each side margin of the sheet.

Obviously, the panel 4 may be made in any desired length, and the roller 10 actuated in any preferred manner, either manually or by power, the drawing showing a bail member 17 pivotally connected to the shaft 11 at the opposite ends of the roller, and formed with one or more arms 18 to which any desired form of connection may 25 be made for actuating the roller 10 back and forth between the frame or form members 7.

It will thus be apparent that I have devised a practical, simple and yet efficient apparatus for producing wall board panels of 30 the character described, in any desired width or length, and at the same time producing the requisite shouldered lip formation along the opposite side margins of these panels. The operation of the apparatus will be obvious in view of the foregoing and without 35 further explanation, and while I have illustrated what I now regard as the preferred form of construction for embodying these improvements, I desire to reserve the right 40 to make such changes or modifications as may fairly fall within the scope of the following claims.

What I claim is:

1. In apparatus for making sheets of wall 45 board having a marginal shouldered lip, a bed providing a supporting surface for receiving the wall board material in plastic condition, a roller adapted for travel across said supporting surface for spreading said 50 material into a layer of uniform thickness, the opposite ends of said roller being pro-

vided with guide projections, and parallel frame members formed with guideways for receiving said guide projections and operating therethrough to maintain said roller at 55 a constant distance above said supporting surface, one end of said roller being formed with an annular enlargement operative to produce said shouldered lip by depressing the material along a continuous line running in the direction of travel of the roller.

2. In apparatus for making sheets of wall board having a marginal shouldered lip, a bed providing a supporting surface for receiving the wall board material in plastic 70 condition, a pair of longitudinal frame members spaced apart a distance equal to the width of sheet to be produced, a roller adapted for travel across said supporting surface between said frame members for 75 spreading said material into a layer of uniform thickness, the opposite ends of said roller being provided with axial guide rolls, said frame members being provided with guideways in parallel relation for receiving 80 said guide rolls and operating therethrough to maintain said roller at a given distance above said supporting surface, one end of said roller being formed with an annular enlargement traveling in abutting relation 85 to the edge of one of said frame members and operative to produce said shouldered lip by depressing the material continuously in the path of travel of said enlargement.

3. In apparatus for making sheets of wall 90 board having a marginal shouldered lip along each side margin of the sheet, a bed providing a supporting surface for receiving the wall board material in plastic condition and provided with longitudinal form members 95 spaced apart a distance equal to the width of sheets to be produced, each of said form members being provided with a bearing groove, and a roller operable to spread the material into a layer of uniform thickness, the opposite ends of said roller having guide projections traveling in the bearing grooves of said form members, for maintaining the roller at a constant distance above said supporting surface, said roller having enlargements operative to produce said shouldered lips by depressing said material during the travel of the roller along each of the side margins of the sheet.

In witness whereof I hereunto affix my 110 signature.

ROBERT J. JOHNSTON.
